his Attorney.

UNITED STATES PATENT OFFICE.

FRANK FAGERBERG, OF LINDSBORG, KANSAS, ASSIGNOR OF ONE-FOURTH TO ERNEST T. NYGREN AND ONE-FOURTH TO ALBERT F. NYGREN, BOTH OF BRIDGEPORT, KANSAS.

ENGINE-PRIMER.

1,081,900.

Specification of Letters Patent. Patented Dec. 16, 1913.

Application filed January 11, 1913. Serial No. 741,411.

To all whom it may concern:

Be it known that I, FRANK FAGERBERG, a citizen of the United States, and a resident of the city of Lindsborg, county of 5 McPherson, and State of Kansas, have invented certain new and useful Improvements in Engine-Primers, of which the following is a specification.

My invention relates to engine primers 10 and particularly to such devices used for facilitating the starting of internal combustion engines.

The object of this improvement is to provide a device of this character which will be 15 simple in its construction and efficient in operation.

Other objects will appear hereinafter.

The invention consists in the combinations and arrangements of parts hereinafter 20 described and claimed.

The invention will be best understood by reference to the accompanying drawing forming a part of this specification, and in which,

25 Figure 1 is a vertical section taken through the primer embodying my invention, Fig. 2 is a horizontal section of the same taken through the central portion, and Fig. 3 is a vertical section taken substantially at 90 degrees from that indicated in Fig. 1.

The preferred form of construction as 30 illustrated in the drawing comprises a body member 4 inclosing a chamber 5 and provided with a removable bottom portion 6. Said bottom portion 6 is preferably screw-threaded to the body 4 and provided with a gasket 7 to furnish a fluid-tight joint.

Two recesses 8 are formed in the upper 35 wall of the receptacle 4 and a recess 9 extends inwardly from the top of said wall and is cut into the recesses 8 thereby forming a passage from the top of the chamber 5 through the top wall of the receptacle 4 to 40 the outside air. A valve seat 10 is fitted tightly in the recess 9 and a spring held valve 11 is fitted in the valve seat 10 and normally remains closed by means of its actuating spring 12. The valve seat 10 is 45 fitted in the body portion 4 securely to form a fluid-tight joint by means of a close fit between said elements, or the same may be 50 made fluid-tight by means of solder or its equivalent.

A passage 13 is provided laterally through 55 the receptacle 4 and extends through the nozzle 14. Said nozzle is provided with screw threads and is adapted to be threaded in the manifold of an internal combustion engine, not shown. The passage 13 is enlarged for a portion of its length and threaded to receive the threaded valve stem 15. The valve stem 15 is provided with a suitable valve coacting with the valve seat 16 formed in the passage 13. A helical spring 60 17 is provided around the extended end of the valve stem 15 under compression to frictionally lock the valve stem 15 in desired positions.

A diagonally extending perforation 18 is 70 provided in the upper wall of the receptacle 4 and communicates with a valve formed in the passage 13. A passage 19 extends longitudinally in the side wall of the receptacle 4 and opens into the same discharge opening 75 with the perforation 18. A lateral perforation 20 is provided in the lower portion of the wall in said receptacle and connects the passage 19 with the lower portion of the chamber 5.

In operation, the nozzle 14 is fitted into 80 the manifold of an internal combustion engine and gasoline or other suitable fuel inserted between the valve 11 and its seat 10 by compressing the spring 12 to permit its passage into the chamber 5. The needle valve 16 is opened to permit of communications 85 through the perforations 18 and 20 and passage 19 from the chamber 5 to the cylinders of said engine. The liquid fuel being 90 heavier than air remains in the lower portion of the chamber 5 and upon moving the pistons of the cylinder of said engine a suction is created in the chamber 5 which draws the liquid fuel through the perforation 20 95 and passage 19 and air through the perforation 18 and through the passage 13 into said engine to facilitate starting thereof.

While I have illustrated and described the preferred form of construction for carrying 100 my invention into effect, this is capable of variation and modification without departing from the spirit of the invention. I, therefore, do not wish to be limited to the precise details of construction set forth, but 105 desire to avail myself of such variations and modifications as come within the scope of the appended claims.

Having described my invention what I claim as new and desire to secure by Letters Patent is:

1. A device of the kind described comprising a receptacle having a bottom portion removably secured thereto; a nozzle near the top portion of said receptacle and adapted to be connected with the cylinder of an engine; a valve in the wall of said receptacle 5 in communication with said nozzle, the upper portion of the wall of said receptacle being provided with a perforation permitting of communication from the upper portion of said receptacle with said valve and a passage in the side wall opening into the lower portion of said receptacle permitting of communication from the lower portion of said receptacle to said valve; and a 10 spring-held valve for admitting air to the upper portion of said receptacle, substantially as described.
2. A device of the kind described comprising a receptacle having a bottom portion removably secured thereto; a nozzle 15 near the top portion of said receptacle and

adapted to be connected with the cylinder of an engine; a valve in the wall of said receptacle in communication with said nozzle, the upper portion of said receptacle being provided with a perforation permitting of communication from the upper portion of said receptacle with said valve and a passage in the side wall opening into the lower portion of said receptacle permitting of communication from the lower portion of said receptacle 30 to said valve, said upper wall being also provided with recesses extending upwardly from the interior of said receptacle and a communication joining the upper ends of said recesses; and a spring held valve in said communication adapted to admit air through said recesses into said receptacle, substantially as described.

In testimony whereof I have signed my name to this specification in the presence of 40 two subscribing witnesses.

FRANK FAGERBERG.
